UNITED STATES PATENT OFFICE.

ARTHUR L. HALLIDAY, OF NEW YORK, N. Y., ASSIGNOR TO THE BIGELOW CARPET COMPANY, OF CLINTON, MASSACHUSETTS.

DESIGN FOR CARPETS.

SPECIFICATION forming part of Design No. 12,243, dated May 3, 1881.

Application filed February 3, 1881. Term of patent 3½ years.

To all whom it may concern:

Be it known that I, ARTHUR L. HALLIDAY, of the city of New York, county of New York, and State of New York, have invented a new and original Design for Carpets, of which the following is a specification.

This invention relates to a new and original design for carpets and similar fabrics; and it consists in the novel grouping and configuration of figures hereinafter more fully described.

The accompanying photograph illustrates a face view of a carpet having my new design.

The figure B is a patterned stripe containing figures d, resembling sharp-pointed leaves with small flowers interspersed, one leaf projecting into the stripe H, and also containing figures b, consisting of a cluster of leaves, from which projects into the stripe H a spray of star flowers and buds. This stripe H contains a bunch of leaves, E, projecting into the stripe B, and having growing from it circular daisy-like flowers p, with slender tufts of grass interspersed between them. The stripe H also contains the figure q, resembling a leaf growing among blades of grass, and with buds and flowers projecting therefrom. It also contains the figure C, resembling light branching sprays of grass with flowers thereon. Between the stripe B and the stripe H runs a patterned band, and between the stripe H and the stripe F runs a band, a, ornamented with a series of parallel lines running lengthwise of the band, and broken at regular intervals by circular ornaments, resembling a spoked wheel. The stripe F has upon it figures h, resembling small leafy branches, and has also crossing it a regular succession of parallel bars. The patterned stripe j runs by the side of the stripe F.

I claim—
